Des. 232,214

Patented July 30, 1974

232,214

DISPOSABLE LITTER CONTAINER OR SIMILAR ARTICLE

Sidney Biderman, 5524 E. Utah Place,
Denver, Colo. 80222

Filed July 3, 1972, Ser. No. 268,700

Term of patent 14 years

Int. Cl. D7—07

U.S. Cl. D7—193

Fig. 1

Fig. 2

Fig. 3

Fig. 4

Fig. 5

Fig. 6

FIG. 1 is a perspective view of a disposable litter container or similar article embodying my new design;

FIG. 2 is a front elevation view of the container of FIG. 1 somewhat reduced in size;

FIG. 3 is a side elevation view thereof;

FIG. 4 is a top view thereof;

FIG. 5 is a bottom view thereof; and

FIG. 6 is a rear elevation view thereof.

The side elevation of the container on the side opposite that shown in FIG. 3 is a mirror image of FIG. 3.

I claim:

The ornamental design for a disposable litter container or similar article, as shown and described.
